BEDCLOTHES HOLDER

Helen D. Calabro, Lexington, Mass.

Application August 7, 1946, Serial No. 689,001

3 Claims. (Cl. 24—72.5)

1

My invention relates, in general, to holding or securing devices, and more particularly has reference to devices for holding or maintaining bedclothes or bed coverings predeterminedly upon a bed.

An important object of my invention is the provision of bedclothes holding means of simple design and facile operation which are capable of predeterminedly maintaining bedclothes, covering elements and the like on a bed in and close to a position of placement most desirable to a person using the bed while holding the bedclothes loosely to allow such a user freedom of movement when covered by the bedclothes yet restraining the bedclothes within the limits of easy reach and from movement towards the sides, foot and head of the bed, said means comprising a pair of similar devices adapted to be frictionally engaged between the mattress support and mattress on opposite sides of a bed and detachably secured at a plurality of locations to the bedclothes to be held.

Other objects of the invention are to provide a bedclothes holder having an anchor member adapted to be frictionally engaged between a mattress support and mattress, clamps adapted to be detachably engaged with the bedclothes to be held, and individual highly flexible connecting members securing each clamp to the anchor member; and also to provide a device of the character described wherein each highly flexible connecting member is secured to the anchor member and an individual clamp and has an overall length sufficient to extend from the anchor to a location above the mattress when the device is operating and with each clamp being secured to its respective connecting member by being disengageably tied thereto at a desired distance from the anchor member whereby the working length of the connecting members may be varied.

Still other objects are to provide in a bedclothes holding device, a pair of highly flexible connecting members each securing an individual clamp to an anchor member adapted to be frictionally held between a mattress support and mattress, the connecting members being designed to permit the clamps to be engaged with a bed covering being held at a location above and to the left and right sides of the anchor member while hanging loosely between the clamps and the anchor member, as well as to provide in such a device means for securing each flexible member to the anchor member whereby tension exerted on the connecting member is transmitted into

the anchor member at a relatively large distance from the periphery of the anchor member.

Further objects of my invention reside in the provision in a bedclothes holder of the character described of an anchor member in the form of a thin and normally flat element having a relatively large surface area and having sufficient flexibility to conform in general to the contacting surface contour of a mattress support and mattress between which it is inserted; and also in the provision of a novel covering for an anchor member, the covering having a tendency to cling to the contacting surfaces of a mattress support and mattress whereby to increase the frictional engagement of the anchor member when in operation between a mattress support and mattress.

Other objects of the invention will in part be obvious and will in part appear hereinafter.

The invention accordingly comprises the apparatus possessing the construction, combination of elements and arrangement of parts which are exemplified in the following disclosure, and the scope of the application of which will be indicated in the claims.

For a fuller understanding of the nature and objects of the invention, reference should be had to the following detailed description taken in connection with the accompanying drawing wherein:

30 Figure 1 is a perspective view of a bedclothes holding device;

Fig. 2 is a perspective view, with parts broken away, of a bed and shows the device of Fig. 1 in operation;

35 Fig. 3 is a longitudinal and partial sectional elevation of the element of the device of Fig. 1 which forms an anchor member for the device; and

Fig. 4 is a partial plan view of a novel base element used in the construction of the anchor member and shows the connecting members of the device secured to the base element.

With reference to Fig. 1, a bedclothes holding device of the character contemplated by my invention is shown as comprising an anchor member 10, a pair of conventional spring-operated detachable clamps 14 and 15, and individual highly flexible connecting members 11 and 12 which respectively secure or connect clamps 14 and 15 to the anchor member.

The anchor member 10 is adapted to be frictionally engaged between a mattress support and mattress of a bed on which bedclothes or a covering element are to be held and clamps 14 and

15 engaged with such bedclothes in a manner which will subsequently appear.

In carrying the invention into effect, I provide a unique and novel anchor member shown in Fig. 3 as having a base or support 17 covered preferably with quilted material 18. The base element is formed of a thin and normally flat material having sufficient flexibility to conform in general to the contacting surface contours of the mattress support and mattress when it is inserted therebetween. Inasmuch as anchor member 10 is held in operating position by frictional engagement between a mattress support and mattress, the expedient of using a thin flexible normally flat material for base element 17 will increase the resistance of the anchor member to disengagement. As examples of suitable material, of which there are many, cardboard and sheet metal may be named for use in forming base element 17.

The covering 18 for the base element has several functions. It improves the appearance of the device and is designed to increase the overall frictional resistance of anchor member 10 when it is operating. By the use of a quilted type of covering, a general conformation of its bearing surface to the contacting surface contour of the mattress support and mattress may be expected to increase the overall frictional resistance offered by the anchor member.

In addition, covering material may be selected which possesses the specific property of offering frictional resistance to mattress ticking. To this end, a rough surfaced material, or a material which has a tendency to cling to the covering of a mattress or mattress support is desired. Many woven and knitted materials of natural and synthetic threads and yarns are suitable. Certain synthetic sheet plastics show a remarkable ability to cling to bed ticking, such as is customarily used in covering mattresses, box springs and the like, and sheet plastics of this character may be named as preferred. Rubber hydrochloride plastics and certain vinyl compounds, including copolymers having vinyl chloride therein, display this ability especially when in sheet form. Other suitable covering materials, not of the plastic sheet type, may be found in wool, cotton, upholstery goods and in rayon and the like.

In making the quilted cover, the space between the inner and outer layer thereof may, if desired, be filled with a fibrous material 19 such as cotton. The covering 18 may be made by doubling a strip of quilted material upon itself and closing the sides of the doubled strip by stitching, after which the base element is inserted in the sheath thus formed and the open end of the covering is closed by stitching.

The shape of anchor member 10 is not of great importance. It may be round, square, rectangular or have an irregular outline. The main requirement is that it have a relatively large surface or bearing area. An anchor member of rectangular shape having overall dimensions of about 10 inches by 4 inches has proven very satisfactory.

A feature of my invention resides in the use of a plurality of clamps, each connected to anchor member 10 by an individual connecting member. It is an essential in this concept that connecting members 11 and 12 be formed of flexible although relatively strong material. In fact, the connecting members should possess the property of flaccidity to a great degree. String, twine, cord and the like are suitable for use as connect-

ing members. Ribbons, bands and strips, formed of quilted or synthetic materials and fabrics, may also be employed. At least from the standpoint of appearance, connecting members formed of ribbon are preferred. The connecting members 11 and 12 are relatively long, and when fully extended may reach from one to two feet from anchor member 10, an extension of about 18 inches satisfactorily meeting most conditions of use. However, the length to which the connecting members may be extended is not critical within the limits indicated, as will be obvious in the light of my full disclosure of the invention.

Connecting members 11 and 12 are each secured near one end to anchor member 10 near the periphery of that portion thereof which is adjacent the side of a bed when the holding device is in operation. For example, when the anchor member is of rectangular shape these connections will be made near an end thereof. Connecting members 11 and 12 may be fixed to covering 18 and to base element 17 at spaced apart locations which are adjacent respective edges thereof. The locations of fixture for the connecting members are chosen so that they will generally be aligned lengthwise of the bed when the anchor member is functioning.

Since both covering 18 and base element 17 are of relatively thin material, and connecting members 11 and 12 are fixed to either at positions close to an edge thereof, it is desirable to secure the connecting members to the covering or base element so that tension exerted on them is transmitted to points inwardly and centrally of the anchor member as a whole and at a relatively large distance from the edges of the anchor member. By such expedient, tearing or rupture of the covering 18 or tearing, bending or distortion of base member 17 and hence the ultimate failure of the anchor member itself may be overcome. By way of illustration, transmission of stress away from the edges of the anchor member, when connecting members 11 and 12 are ribbons, may be effected by fixing each ribbon to covering 18 or base element 17 in a flat condition and so that its longitudinal axis is inclined to the edge of the anchor member and points centrally of the anchor member, or in other words so that the connecting members extend generally in a radial direction outwardly from the anchor member.

As already indicated, covering 18 is formed of a piece of quilted material which may be doubled over upon itself. This procedure forms the opposed outer covering surfaces of covering 18 but leaves the covering open along three edges which are closed by French seaming practices, that is, by turning over a portion or strip of the covering material along and adjacent each unconnected edge and by stitching the outer surfaces and their turned-over portions together with suitable thread. This means that base member 17 is somewhat smaller than covering 18. Of course, covering 18 may be formed of two pieces of quilted material which are superposed on each other which may be secured together by suitably stitching the same, as, for example by French seaming.

In assembling anchor member 10, covering 18 may be partially French seamed to provide three closed or secured edges while leaving open the edge thereof to which connecting members 11 and 12 are to be attached. Base member 17 is then inserted in the partially closed covering 18 and with connecting members 11 and 12 inserted between the edges of covering 18, at the desired inclination to such end, closure is effected while

securing the connecting members to the covering by stitching through the outer surfaces of the covering and its adjacent turned-over portions as well as through the connecting members themselves. In Fig. 1, connecting members 11 and 12 are shown as secured to covering 18 only.

By securing connecting members 11 and 12 to base element 17, a convenient way of correctly positioning them is provided. For example, if the connecting members are ribbons, they are placed in a flat condition on a surface of base element 17 at desired locations and inclinations for fixture thereto and are suitably secured to the base element by fastening means such as staples, rivets or an adhesive. When base element 17, with connecting members 11 and 12 secured thereto, is inserted within covering 18, the connecting members will be held in their desired position of arrangement. The edge of covering 18 left open for insertion of base element 17 with attached connecting members, may be closed by stitching in the manner already described whereby connecting members 11 and 12 will also be secured to the covering although if desired the stitching may stop just short of the connecting members on each side thereof.

Fig. 4 discloses a simple construction whereby connecting members 41 and 42 are quickly and accurately located and secured in desired relation to a modified base element 47 used with an anchor member similar in all other respects to anchor member 10. Base element 47 is notched along opposite sides thereof, the notches 43 being located substantially opposite each other and at a distance from the forward end of element 47 so as to control the positioning of the connecting members which are adapted to be engaged by the notches. In this construction, connecting members 41 and 42 are portions or branches of a long single piece of highly flexible material 40. Notches 43 are of a width sufficient to allow connecting piece 40 to be fully engaged therewith.

Assuming that connecting piece 40 is a long length of ribbon, it is placed in a flat condition under base element 47 in alignment for engagement, with the notches 43 and with the free portions of the ribbon extending substantially equally on opposite sides of the base element. Each free end of the ribbon is then pulled tightly and in a flat condition into engagement with a notch 43 and over the upper surface of the base element 47 in a direction diagonally of the base element and so that the ribbon or connecting piece is crossed with respect to itself in the manner illustrated in Fig. 4, after which the ribbon is secured in this position by a staple 44 or other fastening means engaged with base element 47, and each branch of the ribbon or connecting piece 40 which form the connecting members 41 and 42.

Staples 44 are located at a slight distance from the forward edge or the edge of base element 47 adapted to be nearest a side of a bed when the anchor member is operating, and are suitably positioned in engagement to have tension loads on their respective connecting members 41 and 42 transmitted directly to them. If desired, additional fastening means may be employed, as for example the staple 45 for securing ribbon 40 to base element 47 where it crosses over itself, although such additional means are not essential and are employed to assist in maintaining the piece or ribbon 40 in correctly positioned relation to base element 47.

While in the construction shown in Fig. 4, a

single connecting piece 40 is employed, it is to be observed that by arranging this piece so as to provide a pair of branches an individual connecting member is provided for securing each bedclothes clamp to the anchor member with which base element 47 is associated. In this regard, it may be observed that if the branches of the ribbon or connecting piece 40 are severed at some location between staples 44 and 45 there will be duplicated the previously described embodiment wherein each connecting member is an individual piece and not a branch or portion of a single long piece of material.

Alternately, connecting members 11 and 12 may be secured to base element 17 through the use of eyelets located therein in the spaced apart relation described and an end of each connecting member inserted through its respective eyelet and knotted, although this procedure is not preferred as, for example, it requires that covering 18 be pierced with consequent complications in the manufacture of the device and also leads to an ungainly appearance of the anchor member.

As previously pointed out, a further feature of the invention is the manner in which clamps 14 and 15, and connecting members 11 and 12, are secured to each other. The free end of each connecting member is inserted through the spring 16 of each clamp and is knotted. This leaves clamp 14 or 15 free to slide on its respective connecting member, but nevertheless retained on the connecting member. In most instances when a clamp is adjacent the knotted ends of its connecting member, the overall length of the latter is greater than that required. It is, therefore, desirable to shorten the working length of the connecting member. Such may be accomplished by sliding the clamp relative to its connecting member, while it is retained thereon, towards the anchor member 10 to a desired location and then wrapping the portion of the connecting member between its knotted end and the clamp around an arm of the clamp and disengageably tying the connecting member to the clamp. By this procedure, the position of each clamp 14 and 15 with respect to anchor member 10 is rendered adjustable to the end that the working length of each connecting member 11 and 12 may be selectively varied.

The use and operation of the holding device of Fig. 1 will become apparent in view of the foregoing description, and with reference to Fig. 2 wherein the holding device is shown in working relation to a bed for holding a covering thereon. In Fig. 2 there is shown a bed 20 having a mattress support 24, for example, an enclosed box spring, and a mattress 22 supported thereon. A covering element 23, such as a comforter, blanket or the like, is disclosed as spread out upon the top of the bed and supported on the mattress. Bed 20 is represented so that its foot is at the right of the drawing.

As shown in Fig. 2, an anchor member 10 of a holding device is inserted between mattress support 24 and mattress 22 at a side of the bed with the end thereof to which connecting members 11 and 12 are affixed, that is the forward end, closely adjacent such side and with the anchor so positioned that the aligned spaced-apart locations where connecting members 11 and 12 are secured to the anchor member are generally parallel to the length dimension of the bed. Connecting members 11 and 12 are sufficiently long to permit clamps 14 and 15 to be positioned well above mattress 22 whereby the clamps may be engaged

with the covering element 23 at positions on opposite sides of anchor member 10 towards the foot and the head of the bed as well as above the anchor member, while each connecting member hangs loosely between its respective clamp and the anchor member. Two of the holding devices of Fig. 1 are employed, one on each side of the bed located substantially opposite each other and from about 12 to 27 inches from the foot of the bed although such a distance is not critical. In practice, location of the anchor members at a distance of from 18 to 24 inches from the foot of the bed proves generally satisfactory.

In connecting the device for operating, after anchor member 10 has been positioned between the mattress support and mattress, the clamp nearest the head of the bed, that is clamp 14 of Fig. 2, is attached to a side of covering 23 which is assumed as spread upon the bed in a position most suited to the user. The connecting member 11, if too long, is then drawn up and tied whereby to give the connecting member a working length such that covering element 23 can only move towards the side of the bed most distant from or opposite the holding device to a position wherein its side is adjacent the top of the mattress. Thus, when covering element 23 is in its desired normal position, connecting member 11 will hang loosely along the side of the bed. It is to be noted that with clamp 14 and connecting member 11 arranged in this manner, movement of covering element 23 towards the head of the bed is also limited.

Having affixed clamp 14, clamp 15 is now engaged with a side of covering element 23. Connecting member 12, if necessary, then has its working length adjusted in a manner similar to that described for member 11. The working length for connecting member 12 is selected so as to restrain movement of covering element 23 to the opposite side of the bed from the holding device and also towards the foot of the bed. In this latter regard, the working length of connecting member 12 and the position of engagement of its clamp 15 is such that the clamp will not be moved or will not reach over the end of the bed. Like connecting member 11, the connecting member 12 is adapted to hang loosely over the edge of the bed when covering element 23 is in its normal position.

As a pair of the holding devices of Fig. 1 are employed, a covering element may be predeterminedly maintained on a bed in and close to a position of placement most desirable to a person using the bed while holding the covering loosely whereby to allow such a user freedom of movement when occupying the bed. At the same time, the covering is very securely held by the device, yet is restrained within each reach and is limited in its movement towards the sides and towards the foot and head of the bed whereby the user is continuously kept substantially covered.

These advantages are made possible by securing the holding device to the covering at a plurality of locations and what in effect amounts to connecting these locations individually to the side of the bed. By using a plurality of clamps, certain loads pulling on them are divided so that each clamp receives only a portion of such load. By using an individual connecting member for each clamp, loading of the anchor member is either better or more evenly distributed, all to the end of preventing ready disengagement of

the clamps and displacement of the anchor member of the device from their respective operating positions. In addition, the thin and flexible type of anchor member is designed to offer high frictional resistance whereby it is maintained in desired operating position under adverse conditions.

Further, by securing the clamps to the connecting members rather than having them constantly slidably thereon, and by the use of highly flexible connecting members, means are provided when the covering is moved from its normal position for overcoming undesired entanglement of the clamps and the connecting members with the sides and ends of the bed whereby the clamps become disengaged when it is attempted to return the covering to normal position. Since the connecting members are not resilient they cannot be stretched so as to permit a clamp to be caught on the end of the bed. Furthermore, since each clamp is fixed to what amounts to the end of a tie line without loops or bends therein, substantially no entanglement can occur and any that does would be of such a character that it could be overcome by only a slight pull incapable of disengaging the clamps or the anchor member.

Since certain changes may be made in the above apparatus without departing from the scope of the invention herein involved, it is intended that all matter contained in the above description, or shown in the accompanying drawings, shall be interpreted as illustrative and not in a limiting sense.

It is also to be understood that the following claims are intended to cover all of the generic and specific features of the invention herein described and all statements of the scope of the invention which, as a matter of language, might be said to fall therebetween.

What is claimed is:

40. A device for holding bedclothes on a bed adapted to have a mattress support and mattress, said device comprising a relatively flat anchor member adapted to be frictionally engaged between said mattress support and mattress, a pair of relatively long and highly flexible connecting members extending from said anchor member and fixed thereto at spaced apart locations near an edge of the anchor member in converging relation from said edge towards the center of the anchor member, and a pair of clamps, one for each connecting member, each clamp having coil spring operating means and being adapted to be detachably engaged with bedclothes to be held on said bed, each connecting member extending through the coil spring operating means of its respective clamp whereby said clamp is slidable on the connecting member with which it is associated and is adjustably securable to said connecting member between said anchor member and the free end of the connecting member by the tieing of said connecting member to said clamp.

45. A device for holding bedclothes on a bed adapted to have a mattress support and mattress, said device comprising an anchor member having an element of relatively large area which is adapted to be frictionally held between said mattress support and mattress and which is formed of normally flat but flexible sheet material, a cover of a thin pliable material engaged over said element and adapted to increase the resistance of said element to movement relative to surfaces in pressure contact therewith, a pair of relatively long and highly flexible connecting members extending from said anchor member and fixed

thereto at spaced apart locations near an edge of the anchor member in converging relation from said edge towards the center of the anchor member, and a pair of clamps, one for each connecting member, each clamp being adapted for detachable engagement with bedclothes to be held on said bed and each clamp being attached to its respective connecting member and securable thereto at an adjusted location between said anchor member and the free end of the connecting member by the tieing of said connecting member to said clamp.

3. A device for holding bedclothes on a bed adapted to have a mattress support and mattress, said device comprising an anchor member having an element of relatively large area which is adapted to be frictionally held between said mattress support and mattress and which is formed of normally flat but flexible sheet material, a pair of relatively long and highly flexible connecting members extending from said anchor member and fixed thereto at spaced apart locations near an edge of the anchor member in converging relation from said edge towards the center of the anchor member, a cloth-like cover substantially entirely covering said element and adapted to increase the resistance of said element to movement relative to surfaces in pressure contact therewith, said cover being provided with a pair of openings, one for each connecting member, at the end of said cover adjacent the edge of said anchor member near which said connecting members are affixed to the anchor member, each connecting member extending through its respec-

tive opening and lying on a face of said element and in contact with an inner face of said cover, and a pair of clamps one for each connecting member, each clamp being adapted for detachable engagement with bedclothes to be held on said bed and each clamp being attached to its respective connecting member and securable thereto at an adjusted location between said anchor member and the free end of the connecting member by the tieing of said connecting member to said clamp.
